UNITED STATES PATENT OFFICE

CORNELIS A. H. MULDER, OF EINDHOVEN, NETHERLANDS, ASSIGNOR TO GENERAL ELECTRIC COMPANY, A CORPORATION OF NEW YORK

METHOD AND APPARATUS FOR COILING WIRE

Application filed September 7, 1929, Serial No. 391,099, and in the Netherlands September 25, 1928.

It is well known that wire can be coiled into a helix by using a core around which the wire is wound. In case it is desired to wind helices of large diameter, such as springs, the 5 core is usually a rod; however, if it is desired to wind a long helix of small diameter, such as is commonly employed as a filament for electric incandescent lamps, the core is a wire of indefinite length, around which the 10 filament wire is wound. The process in the first case is not continuous, while in the second case difficulties may be encountered in removing the core.

Coiling devices are known for coiling a 15 wire into the shape of a helix without using a core, but in which the helix is made by a rotating spine which operates in conjunction with one or more rollers. The wire is brought in between the surfaces of the rollers and the 20 surface of the spine and the rollers engage it at such a point and in such a way that the wire is not subjected to frictional forces when guided between these surfaces.

In accordance with the method of the 25 invention the wire is moved forward between at least two shaping-surfaces, which cooperate to form a guide for a certain predetermined length of the wire, and whereby at least one of these surfaces has a relative motion with reference to the path which the 30 wire is following. Thus, the wire will be subjected to a force due to friction which will cause the desired transformation or shaping to take place, or which at least will assist in 35 it. The guiding of a certain predetermined length of the wire is in contradistinction to the point or purely local guiding of the wire in the previous coiling devices above described. The length of the path along which 40 the wire is guided can, for example, be about the same as the diameter of the helix into which it is being coiled.

According to the present invention the wire 45 is guided along the shaping surfaces in such a manner that it is gradually or substantially gradually transformed from a straight wire into a helix. This method has the advantage that the wire may be fed into the apparatus with low tension, and further, that the wire 50 will suffer less than it would when trans-

formed suddenly from a straight wire into a helix. Experience has shown that there exists a maximum speed limit for winding at which the wire breaks, due to the sudden transformation from a straight wire into a 55 helix. By using a gradual transformation this maximum speed may be raised and thus it will be possible to obtain an appreciable increase in the speed of coiling.

During the coiling process the shaping surfaces exert on the wire forces due to friction which can be regulated by changing the pressure of the surfaces on the wire by hydraulic means or by springs.

After the wire has assumed the shape of 65 a helix it may, according to the invention, be guided for a certain distance along the surface of a cylinder or of a slightly divergent cone, so that the wire will be held as a certain definite helix for a time and will, thereafter, 70 have an opportunity to unbend gradually to a slight extent to relieve strains. Also, due to this arrangement the helix will be subjected to a certain force propelling the helix lengthwise.

According to the invention, one or both 75 of the shaping-surfaces can be made as rotating-surfaces. Where only one of these surfaces is a rotating-surface the other surface is made of such a character that both 80 surfaces cooperate and together form a guide for a certain length of the wire. The axes of rotation of the rotating surfaces may be in alignment or they may be parallel to each other, or they may intersect or cross each 85 other. This latter arrangement is recommended in case it is desired to manufacture helices with a pitch which is only a little greater than the diameter of the wire.

According to the invention, the shaping 90 surfaces can have a relative motion with regard to each other. The pitch of the helix can be controlled both by this motion and by the rate of feed of the wire which is to be coiled. However, as the path which the wire 95 follows between the shaping surfaces and the forces which act upon the shaping surfaces may be changed due to this control, it is desirable that care be taken that one of the shaping surfaces can change its position 100

with regard to the other in order to agree with this change, and therefore, it may be desirable to exert a cross-force on one of the shaping surfaces.

According to the invention, a lubricant can be applied during the coiling, either by oiling the shaping surfaces or by oiling the wire itself. This has the advantage that the shaping surfaces and the wire are subjected to less wear and, further, that the coefficient of friction is more constant than in the case of surfaces which are not lubricated.

The wire may be heated during the coiling process. For example, if tungsten wire is heated to 700 degrees (centigrade), it will become appreciably softer and after its transformation it will spring back to only a very slight extent. If the shaping surfaces retain the same or approximately the same hardness at this temperature as at room temperature the coiling will take place easier and the wear of the shaping surfaces will be small. It is preferable to heat the wire by electricity and to use the shaping surfaces, or the device by which the wire is fed, as electrodes, in order that the heating of the electrodes may be comparatively slight while the heating of the wire is great.

The helices may be manufactured with or without tension. When manufacturing springs, a tension is usually desirable. According to the invention, this tension can be obtained by making the speed of feed of the wire a function of the force by which it is pulled by the shaping surfaces. By retarding the feed of the wire in a suitable manner, as for example, by applying brakes, it is possible to obtain any desired tension in the wound wire. Leather makes a desirable brake, with the advantage that the coefficient of friction increases with the speed of feed of the wire, and consequently the coiling is very uniform.

Apparatus constructed according to the present invention comprises at least two shapers of which the cooperating and substantially complementary surfaces form together a guide for a certain predetermined length of the wire fed from a reel of the wire to be coiled, and also means to produce a relative motion between at least one of these shapers and the path which the wire is following.

The supply of wire can be mounted on a spool which rotates around the shapers, in which case shapers may be stationary, or may be given a relative motion with reference to each other. In this case it is possible to take precautions so that the manufactured helix does not rotate as it comes out of the apparatus.

It is also possible to keep the supply of wire stationary and to give a movement to the shapers. In this case, these shapers may

or may not have a relative motion with regard to each other. The manufactured helix will, in this case, rotate as it comes out of the apparatus.

The shapers can be designed in such a manner that the wire will be transformed gradually or nearly gradually from a straight wire to a helix, and in this case both shapers may preferably be made as rotating surfaces. However, this is not essential, as it is also possible to make only one of the shapers as a rotating surface and to design the other shaper in such a way that it, together with the rotating surface, forms a guide for the wire over a certain distance. In the case where both shapers are constructed as rotating surfaces they may be installed with their axes of rotation in the same line, or parallel to each other, or even intersecting or crossing each other. This latter arrangement is recommended in case it is desired to manufacture helices with a small pitch.

According to the invention it is possible to increase the friction exerted on the wire by the shapers by installing a device which presses the shapers toward each other and increases the pressure which is exerted by the shapers on the wire.

According to one construction in accordance with the invention, one of the shapers has a cone-shape, while the other has the shape of a single rotating hyperboloid. In order to be assured of the correct position of the one shaper with reference to the other, and also in order to be able to regulate the pitch of the helix in a convenient manner the shapers, according to the invention, can be mounted in such a way that they will align themselves with reference to each other.

According to the invention a helix guiding device with a cylindrical or slightly diverging surface can be used in conjunction with the shapers. This device may form part of one of the shapers and may also be installed in such a way that its surface joins or forms a continuation of the surfaces of these shapers.

In accordance with one embodiment of the invention the shapers are installed in a bath of oil, or the wire runs through a lubricating device.

In accordance with another embodiment of the invention means are provided to heat the wire during the coiling. This heating can be done electrically by using the shapers or the reel of wire as electrodes and by conducting the current from one shaper through the wire to the other shaper or to the reel of wire.

The invention will best be understood in connection with the accompanying drawing and will be explained in detail by referring to the drawing which shows some of the forms in which the device may be constructed in accordance with the invention, and in which

Fig. 1 is a perspective view of the shapers

of one form of the device with two rotating shapers;

Fig. 2 is a perspective view of the shapers of a second form of the device with one of the shapers stationary;

Fig. 16, an enlarged view of a wire coiled by the previously known methods; and

Fig. 17, an enlarged view of a wire coiled in accordance with this invention.

The framework and driving mechanism of a coiling machine constructed in accordance with this invention are substantially the same as is commonly used in coiling machines. The shapers by means of which the wire is coiled into a helix are mounted in the desired relation to each other, one or both being

mounted in any well-known way so as to rotate, and to be driven by belts or similar driving mechanism. Fig. 1 shows two shapers 10 and 11, both of which rotate in the same direction about axes of rotation which inter-

sect or cross near the point where the coil is formed. For clearness of illustration the bearings, supporting framework, and driving mechanism, for the two shapers are omitted. The shaper 10 is conical, and the

cooperating shaper 11 has the form of a hyperboloid with a central throat or opening slightly larger than the helix formed when the wire is coiled. A helix guide 12, which is tubular and has a slightly divergent bore,

is joined at its small end to the hyperboloid

shaper 11 to register with the central throat or opening in that shaper and to receive the helix as fast as it is formed by the shapers. As shown in the drawing, the wire 13 to be

coiled into a helix is located between the two cooperating shapers 10 and 11, and will be guided by them for a certain distance or part of its length extending from A to B

as shown in this figure, along a spiral path terminating in an arc of a circle corresponding to the outer diameter of a turn of the helix. As the wire passes lengthwise along the portion A B of its path between the shapers it will be transformed gradually

from a straight wire into a helix which will be delivered through the central throat or opening in the shaper 11 into the tubular helix guide 12, which, as best shown in Fig.

3, has a cylindrical bore from C to D, and beyond D it flares slightly so that its bore

is slightly conical and is larger at the delivery end than at D. The shapers 10 and 11 are mounted in such a manner that their axes intersect or cross, as clearly shown in

Figs. 1 and 3. Due to their rotation both shapers have a movement relative to the path followed by the wire 13, and their relative

speeds of rotation may be such that they also have a definite speed of movement with reference to each other.

Fig. 2 shows another construction in which the rotating shaper 10 operates in conjunction with a stationary shaper 15 of the same general contour as the shaping surface of

the shaper 11 and so set with relation to the conical shaper 10 that the wire 13 passing between these two shapers is guided for

a certain part of its path by the shapers, much as in Fig. 1, and is converted into a helix. Fig. 4 shows the shaper 11 modified, if desired, by the omission of the cylindrical portion C D of the bore, so that the helix is delivered directly into the diverging

bore of the helix guide 12.

Fig. 5 shows a modification form of the shaper 11 of Fig. 3 in which the helix guide 12 is independent of the shaper 11, so that if desired the shaper and helix guide may

have a relative motion about the same axis of rotation.

A modified form of the shaper 10 is shown in Fig. 6. In this modification different parts of the shaping surface may move relatively to each other during the bodily rotation of the shaper as a whole. One way of

securing such a relative movement of parts of the shaper surface is to construct the shaper 10 in two parts, one a tubular portion

17 having a shaping surface like a frustum of a cone, and the other a conical tip at the end of the portion 17 to form the apex of

the cone and mounted on a shaft 18 extending through the bore of the tubular portion

17 so that the portion 17 and the tip 18 may both be driven separately and at different

speeds, so that the tip 18 has, during the rotation of the shaper, a movement relative to the tubular portion 17.

In the particular embodiment of the invention shown in Fig. 7 the parts of the machine are mounted on a table or frame F. In this figure the shapers 10 and 11 are set substantially as shown in Figs. 1 and 3, so that their axes of rotation intersect. The shaper 10 is supported by a self-aligning roller bearing 21, and is driven by the pulley 22. The roller bearing 21 is fastened to the end of a stud 23 which is mounted on and is adjustable along a quadrant or curved member 24 bent to the arc of a circle of which the center is at the apex of the conical shaper 10. The rotatable shaper 11 and its bearings forms part of a structure somewhat like the headstock of a lathe, and is made in the end of a tubular shaft 11a by making a recess shaped as indicated at 11 in Figs. 1 and 3, the bore of the tubular shaft forming the helix guide 12 shown in Figs. 3 and 4. A perforated thrust block 25 rests in a recess in the other end of the shaft 11a with its perforation in registry with the bore of the shaft so that the helix can pass through the shaft lengthwise and out through the block. By means of this thrust block 25, which is secured to a crossbar controlled by springs 26 attached to the ends of the crossbar and to the one of the bearing blocks of the headstock, the shaft 11a with the shaper 11 on its end is yieldably pressed against the conical shaper 10. The shaft and the shaper 11 are rotated by the pulley 27 secured to the shaft, and the wire 13 is fed into place between the shapers 10 and 11 by a wire feed device comprising feed rolls 28 and 29, preferably driven at a speed which bears a definite and predetermined speed to the speed of rotation of the shapers 10 and 11 so that the speed of the wire feed is a function of the pull exerted on the wire by the rotating shapers. The roller bearing 21 permits the shaper 10 to align itself properly in the cavity of the shaper 11 and to contact at its apex at a point inside the helix with the shaper 11. The angle of intersection of the axes of rotation of the two shapers can be adjusted by moving the stud 23 on the quadrant member 24.

The shapers 10 and 11 and associated mechanism may be driven from a drive shaft 30 mounted on the frame F and provided with pulleys 30a and 30b, preferably differing in size, for driving through belts the pulley 22 for the shaper 10 and the pulley 27 for the shaper 11. The drive shaft may also drive the feed rolls 28 and 29 through a worm gear drive 30c. In the particular arrangement shown the shaper 10 is driven faster than the shaper 11, but both shapers may be driven at the same speed, or the shaper 11 can be driven faster than the shaper 10, if desired.

The wire may conveniently be heated during the winding by insulating the headstock

and the quadrant member 24, or the wire feed rolls, from the frame and connecting the headstock to one terminal of the secondary winding of a transformer G, the primary winding of which is fed by any convenient source of current, the other terminal of the secondary being connected to the feed rolls. If it is desired to heat the wire by using the shapers as electrodes and conducting the current through the wire from one electrode to the other, the terminal of the transformer now connected to the feed rolls should be connected to the quadrant member 24, as shown in Fig. 7, in which case the wire is heated by the current flowing through it from the shapers to the feed rolls.

The wire may be lubricated to facilitate winding and maintain the coefficient of friction between the shapers and the wire substantially constant, thereby permitting more accurate coiling and also reducing the wear on the shapers. The wire may be lubricated by a lubricator H consisting of a grooved roller in a cup of lubricant before it passes to the shapers, or the shapers may be submerged in oil, as shown in Fig. 8, in which the shapers are mounted in an oil tank O containing enough oil to keep the shapers submerged.

In the modification shown in Fig. 9 a winding spool 31 rotates on a ball-bearing around a post 32, one end of which constitutes a shaper 10 which is conical. The post 32 projects from a holder 33 adjustable on a curved or arc-shaped member 34. A wire reel 35 is mounted on the winding spool 31 and the wire 13 which is to be wound is fed from the reel to the shapers 10 and 11. By selecting the relative speeds correctly the spiral wound in this manner will not rotate as it leaves the shaper 11.

The modification shown in Fig. 10 has a pin 37 with its end conical to form the shaper 10, and also has a winding spool 38 with a wire reel 39. This winding spool rotates on the post 40 which is stationary and which is mounted on the support 41. The pin 37 with the conical end forming the shaper 10 is adjustably mounted on the winding spool by means of the curved plate 42. This makes it possible to set the pin 37 in such a manner with reference to the shaper 11 that the axes of rotation of the shapers intersect or cross each other. In order to fulfill this last requirement it is desirable that the plate 42 be universally adjustable on the spool 38, so that it can be set in all possible positions on the winding spool 38. If the winding spool 38 is now rotated the pin 37 will follow this rotation and the shaper 10 will also rotate.

The diameter of the wound helix is fixed by widening or narrowing the cylindrical or slightly divergent part of the helix guide 12. The pitch of the helix can be adjusted by

changing the shape or the relative position of the shaping surfaces, but this can be also accomplished by changing the speed of feed of the wire and/or the speed of the shaping surfaces as indicated by the vector diagrams Figs. 11, 12, and 13, showing the relative speeds and the forces exerted on the wire.

In Fig. 11 the speed at a certain spot of the shaping surface is indicated by V , and the speed of feed of the wire by V_1 . The relative speed of the wire with regard to the shaping surface has a magnitude and direction, which are indicated by a_1 and b_1 in Fig. 11.

In Fig. 12 the speed of rotation of the shaping surface is the same, but the speed of feed of the wire is less, that is V_2 is less than V_1 . The relative speed is again indicated by a_2 and b_2 .

In Fig. 13 the speed of feed of the wire a^3 is equal to the speed V_1 in Fig. 11. The speed of rotation of the shaping surface is now V_3 , which is less than V . The relative speed is again indicated by a_3 and b_3 . The force of the friction exerted by the shaping surface will be a function of its relative speed and is indicated in the figures by W_1 and W_2 and W_3 respectively. It is less in Fig. 12 than in Fig. 11 and in Fig. 13 it is directed more crosswise to the path of the wire than in Fig. 11, which shows that with a definite speed of the shaping surface the pitch can be made larger by decreasing the speed of feed of the wire, and that the pitch can be made smaller by decreasing the speed of the shaping surfaces with reference to the path of the wire, and vice versa.

By periodical change of these factors, it is possible to wind helices with varying pitch. It is even possible to manufacture helices with interposed straight parts in this manner. However, this also is possible by making a certain definite selection of the speeds of the shaping surfaces with regard to the path of wire, of the shape of the shaping surfaces, and of their relative position, of the speed of feed and direction of feed of the wire, so that helices may even be made consisting of coils wound in opposite directions. After a certain number of these turns have been made, they will unbend in the slightly divergent rotating helix guide and thereby exert a comparatively strong pulling force, which may reach such a value, that the wire is pulled through between the shaping surface with the result that a turn with a large pitch will appear. However, when this takes place, then the adjoining turns have moved on over such a distance that they no longer exert a pulling force, and consequently the shaping surfaces will proceed to wind the wire again as a helix. In this manner straight or practically uncoiled parts can be made at definite intervals.

As indicated in Figs. 14 and 15 the shapers may be mounted in such a manner that their

axes of rotation either coincide, as in Fig. 14 or are parallel as in Fig. 15.

The wire wound into a helix in accordance with the method of the invention shows as a characteristic one or more polished figures in the shape of ribbons or lines, which are caused by the pressure or friction of the shaping surfaces. These figures may be observed clearly in a microscope, as shown in Fig. 16, which is an enlargement of a wire wound in accordance with the present known method, and Fig. 17, which is an enlargement of a wire wound in accordance with the invention.

What I claim as new and desire to secure by Letters Patent of the United States is:

1. The method of coiling a wire into a helix without a core, which comprises passing a wire lengthwise between two adjacent shaping surfaces which cooperate to guide the wire for a predetermined distance along and toward the inner end of a spiral path having its inner end curved to substantially an arc of a circle, simultaneously moving at least one of said surfaces and the wire in said path relatively to each other and transversely of said path and thereby bending the wire into a coil, and moving said coil bodily lengthwise for a predetermined distance along and in contact with cylindrical walls, which form an extension of one of said wire shaping surfaces.

2. The method of coiling a wire into a helix without a core, which comprises passing a wire lengthwise between two adjacent shaping surfaces which approximately complement each other and rotate in the same direction at different speeds about axes which intersect and which cooperate to guide the wire between them for a predetermined distance along and toward the inner end of a spiral path having its inner end curved to substantially an arc of a circle and thereby bending the wire into a coil, and simultaneously moving at least one of said surfaces and the wire in said path relatively to each other and transversely of said path.

3. The method of coiling a wire into a helix without a core, which comprises passing a wire lengthwise between two adjacent shaping surfaces which approximately complement each other and rotate in the same direction at different speeds about intersecting axes, said shaping surfaces being in contact at a point inside the helix and cooperating to guide the wire between them for a predetermined distance along and toward the inner end of a spiral path having its inner end curved to substantially an arc of a circle and thereby bending the wire into a coil, and simultaneously moving at least one of said surfaces and the wire in said path relatively to each other and transversely of said path.

4. The method of coiling a wire into a helix without a core, which comprises passing a

wire lengthwise between two adjacent shaping surfaces which approximately complement each other and which have a relative motion with reference to each other and which cooperate to guide the wire between them for a predetermined distance along and toward the inner end of a spiral path having its inner end curved to substantially an arc of a circle and thereby bending the wire into a coil, and simultaneously moving at least one of said surfaces and the wire in said path relatively to each other and transversely of said path.

5. The method of coiling a wire into a helix without a core, which comprises passing lengthwise between two adjacent shaping surfaces which approximately complement each other a wire at a speed which is a function of the pull exerted on said wire by said surfaces and guiding the wire between said surfaces for a predetermined distance along and toward the inner end of a spiral path having its inner end curved to substantially an arc of a circle to bend the wire into a coil, 10 and simultaneously moving at least one of said surfaces and the wire in said path relatively to each other and transversely of said path.

6. The method of coiling a wire into a helix without a core, which comprises passing lengthwise between two adjacent shaping surfaces which approximately complement each other a wire at a speed which is a function of the pull exerted on said wire by said surfaces, guiding said wire between said surfaces for a predetermined distance along and toward the inner end of a spiral path having its inner end curved to substantially an arc of a circle to bend the wire into a coil, 20 simultaneously moving at least one of said surfaces and the wire in said path relatively to each other and transversely of said path, and varying the pitch of said coil by varying the relative speeds of said shaping surfaces.

45. The method of coiling a wire into a helix without a core, which comprises passing lengthwise between two adjacent shaping surfaces which approximately complement each other a wire at a speed which is a function of the pull exerted on said wire by said surface, guiding the wire between said surfaces for a predetermined distance along and toward the inner end of a spiral path having its inner end curved to substantially an arc of a circle to bend the wire into a coil, simultaneously moving at least one of said surfaces and the wire in said path relatively to each other and transversely of said path, and varying the pitch of said coil by varying the relative speeds of said wire and said shaping surface.

60. 8. In a wire-coiling machine, the combination of a conical shaper, a cooperating shaper having a recess in the form of a hyperboloid which substantially complements said conical shaper to form a guide for a pre-

determined length of a wire between said surfaces, means for feeding a wire lengthwise between the surfaces of said shapers, and driving mechanism for actuating one of said shapers to produce between its surface and said wire a relative movement transversely of the path of said wire.

9. In a wire-coiling machine, the combination of two adjacent rotatable shapers having opposing surfaces which are in contact near their centers and which substantially complement each other to form a guide for a predetermined length of a wire between said surfaces, bearings for said shapers constructed to permit said shapers to align themselves with each other, means for feeding a wire lengthwise between the surfaces of said shapers, and driving mechanism for actuating said shapers to produce between their surfaces and said wire a relative movement transversely of the path of said wire.

10. In a wire-coiling machine, the combination of two adjacent shapers having opposing surfaces which substantially complement each other to form a guide for a predetermined length of a wire between said surfaces, one of said shapers being concave and having a central throat, a tubular helix guide having a cylindrical bore with walls which form an extension of the walls of said throat, 95 means for feeding a wire lengthwise between the surfaces of said shapers, and driving mechanism for actuating one of said shapers to produce between its surfaces and said wire a relative movement transversely of the 100 path of said wire.

11. In a wire-coiling machine, the combination of two adjacent shapers having opposing surfaces which substantially complement each other to form a guide for a predetermined length of a wire between said surfaces, one of said shapers having the form of a hyperboloid with a central throat and a tubular extension with a cylindrical bore, means for feeding a wire lengthwise between the surfaces of said shapers, and driving mechanism for actuating one of said shapers to produce between its surface and said wire a relative movement transversely of the 110 path of said wire.

12. In a wire-coiling machine, the combination of two shapers mounted to rotate about axes that intersect, said shapers having opposing surfaces which substantially complement each other to guide a wire between said surfaces for a predetermined distance along a spiral path terminating in a curve which forms an arc of a turn of a helix, means for feeding a wire lengthwise between the surfaces of said shapers, and driving mechanism 120 for actuating said shapers to produce between their surfaces and said wire a relative movement transversely of the path of said wire.

13. In a wire-coiling machine, the combination of two shapers having opposing sur-

- faces which substantially complement each other to guide a wire between said surfaces for a predetermined distance along a spiral path terminating in a curve which forms an arc of a turn of a helix, means for feeding a wire lengthwise between the surfaces of said shapers, and driving mechanism for actuating said shapers to produce a relative movement between them and thereby a relative movement between their surfaces and said wire transversely of the path of said wire. 5
14. In a wire-coiling machine, the combination of two adjacent shapers having opposing surfaces which substantially complement each other to form a guide for a predetermined length of a wire between said surfaces, means for pressing said shapers toward each other to maintain them in engagement with the wire between them, a winding spool mounted to rotate about an axis extending through the centers of said shapers, and thereby wind a wire on said spool into place between said shapers, and driving mechanism for said winding spool. 15
15. In a wire-coiling machine, the combination of two adjacent shapers having opposing surfaces which substantially complement each other to form a guide for a predetermined length of a wire between said surfaces, means for pressing said shapers toward each other to maintain them in engagement with the wire between them, a winding spool mounted to rotate about an axis extending through the centers of said shapers, one of 20 said shapers being mounted to rotate with said winding spool, and driving mechanism for driving said winding spool and said shaper. 25
16. In a wire-coiling machine, the combination of two adjacent insulated shapers having opposing surfaces which substantially complement each other to form a guide for a predetermined length of a wire between said surfaces, means for pressing said shapers toward each other to maintain them in engagement with the wire between them, a source of current with its terminals connected to said shapers to pass current from one shaper to the other to heat the wire between them, and driving mechanism for actuating said shapers. 40
17. In a wire-coiling machine, the combination of two adjacent shapers having opposing surfaces which complement each other and form a guide for a predetermined length of wire between said surfaces, a self-aligning bearing on which one of said shapers rotates, means for feeding a wire lengthwise between said surfaces, and driving mechanism for 45 said rotatable shaper. 50
18. In a wire-coiling machine, the combination of two adjacent shapers having opposing surfaces which complement each other and form a guide for a predetermined length 55 of wire between said surfaces, said surfaces being in contact near their centers, a supporting member curved to the arc of a circle of which said point of contact is the center, a self-aligning bearing adjustable along said member and on which one of said shapers is mounted to rotate, means for feeding a wire lengthwise between said shaper surfaces, and driving mechanism for said rotatable shaper. 70
- In witness whereof, I have hereunto set my hand this 17th day of August, 1929. 75
